UNITED STATES PATENT OFFICE.

CHARLES O. BOUVETT, OF NEW CASTLE, DELAWARE.

SALT-CELLAR.

933,690.

Specification of Letters Patent.

Patented Sept. 7, 1909.

Application filed February 20, 1909. Serial No. 479,027.

To all whom it may concern:

Be it known that I, CHARLES O. BOUVETT, a citizen of the United States, residing at New Castle, in the county of Newcastle and State of Delaware, have invented new and useful Improvements in Salt-Cellars, of which the following is a specification.

This invention relates to receptacles adapted for the reception of condiments such as salt, pepper and the like, and the object of the invention is to provide a receptacle of this character with a perforated cap or closure having an agitator blade adapted to be extended within the receptacle and provided with a suitable handle projecting outside of the cover whereby the agitator may be rotated within the receptacle to stir the condiment and thoroughly agitate the same so as to allow a free passage of the condiment through the perforated top or closure.

With the above, and other objects in view which will be more apparent as the description progresses, the invention resides in the novel construction and arrangement of parts hereinafter fully described and claimed.

In the accompanying drawing, Figure 1 is a side elevation of a salt cellar constructed in accordance with the present invention. Fig. 2 is a central vertical sectional view of the same. Fig. 3 is a similar section illustrating a slightly modified form of the device. Fig. 4 is a horizontal section upon the line 4—4 of Fig. 3.

In the drawings the numeral 1 designates the cellar or receptacle. This receptacle 1 may be constructed of any desired material and has its upper open mouth provided with a reduced threaded portion 2. The lower portion or floor of the cellar may be, as illustrated in Fig. 3, provided with a central depression or agitator seat, designated by the numeral 3.

The numeral 4 designates the top or cap of the cellar. This cap 4 is provided with the usual perforated condiment outlets 5, and is also provided with a depending flange 6 having interior threads adapted to engage with the threads 2 of the receptacle 1. The cap 4 is also provided with a central opening 7 which is adapted for the reception of the handle member 8 connecting an agitator member 9. The agitator 9, as illustrated in Fig. 4 of the drawing, comprises a flattened body portion having its ends rounded

in opposite directions, as designated by the 55 numeral 10. The body portion of the agitator member 9 is approximately centrally provided with a transverse opening 11, and this opening is adapted for the reception of the wire composing the handle 8. The handle 60 8 may be constructed of a single strand of wire, as illustrated in Fig. 3 of the drawing, or may be constructed of several strands of wire twisted upon themselves, as illustrated in Fig. 2 of the drawing and as both are of 65 a substantially similar formation the reference numerals and method of connection with the agitators are precisely similar. The strand wire comprising the handle and the agitator support is first passed through the 70 opening provided by the agitator 9, and is from thence brought upwardly upon both sides of the agitator and passed through the central orifice 7 of the cap 4. The strands of wire are then bent in opposite directions, 75 in a substantially horizontal plane and from thence are bent upwardly toward each other and twisted together in a line with the plane of the members secured upon each side of the agitator 9, and these strands may be bent 80 away from each other and downwardly terminating approximately in line with the horizontal offset members adjacent the cap 4. A suitable washer 12 is provided between the horizontal offset portions of the wire and the 85 top of the cap so as to allow for the free rotation of the handle and the agitator within the receptacle. While I have illustrated and described the handle 8 constructed as above, it is to be understood that I do not 90 wish to limit myself to this exact formation as other designs may be used with equal efficiency.

In Fig. 3 it will be noted that the agitator 9 extends nearly to the bottom of the receptacle 1 and is provided with a central depending bearing 13 adapted to be positioned within the recess 3 of the receptacle.

From the above description, taken in connection with the accompanying drawing it 100 will be noted that I have provided an extremely simple and effective device for the purpose intended, one wherein the condiment within the receptacle may be readily agitated and stirred so as to thoroughly loosen the 105 grains of the condiment and allow an easy and free passage through the openings 5 of the cap 4, one which may be constructed at

a small cost and one which may be readily and easily applied to the caps of similar receptacles now in general use.

Having thus fully described the invention 5 what is claimed as new is:

1. The combination with a condiment receptacle, a perforated cap for the receptacle, of an agitator comprising a flattened body portion and having its ends adjacent the 10 wall of the receptacle bent in opposite directions, said agitator being provided with a central orifice, a wire member engaging the orifice and projecting upon each side of the body of the agitator through the perforated cap and having its ends bent to form 15 a handle, substantially as described.
2. A condiment receptacle having its bottom provided with a centrally arranged depression, a perforated cap for the receptacle,

an agitator member extending between the 20 perforated cap and the bottom of the receptacle, said agitator having a flattened body portion and having its lower end provided with a bearing adapted to engage the recess in the bottom of the receptacle, said 25 agitator having its body portion provided with an opening, a wire member engaging the opening and extending upon both sides of the agitator through one of the perforations of the cap, and said projecting portions being bent to form a handle, substantially as described.

In testimony whereof I affix my signature in presence of two witnesses.

CHARLES O. BOUVETT.
